J. F. TEEL,
AUXILIARY AIR AND STEAM INLET VALVE FOR INTERNAL COMBUSTION ENGINES.
APPLICATION FILED APR. 10, 1916.
1,281,311.

Patented June 26, 1917.

UNITED STATES PATENT OFFICE.

JOHN F. TEEL, OF LOS ANGELES, CALIFORNIA, ASSIGNOR TO (MRS.) LAURA G. FIXEN,
OF LOS ANGELES, CALIFORNIA.

AUXILIARY AIR AND STEAM INLET VALVE FOR INTERNAL-COMBUSTION ENGINES.

1,231,311.

Specification of Letters Patent. Patented June 26, 1917.
Application filed April 10, 1916. Serial No. 90,168.

To all whom it may concern:

Be it known that I, JOHN F. TEEL, a citizen of the United States, residing at Los Angeles, in the county of Los Angeles and State of California, have invented new and useful Improvements in Auxiliary Air and Steam Inlet Valves for Internal-Combustion Engines, of which the following is a specification.

10 This invention relates to an auxiliary air and steam valve for internal combustion engines.

During the operation of internal combustion engines, the mixture of the charge becomes too rich for complete combustion, and it deposits carbon in the cylinders and otherwise prevents ideal working conditions of the engine.

It is a well known practice in the art under such conditions to introduce additional air into the engine cylinders to dilute the charge to facilitate combustion thereof and to introduce steam into the cylinders to prevent the deposit of carbon in the cylinders and, by the expansive action of the steam, to prolong and equalize the effectiveness of the charge acting upon the engine pistons.

It is an object of my invention to provide a simple unitary auxiliary valve adapted to be placed on the engine manifold intake and controlled by a single controlling element by means of which valve, air or steam may be independently introduced into the engine cylinders, or air and steam combined in different proportions introduced into the cylinders to overcome the objectionable working conditions of the engine as above specified.

40 Other objects will appear hereinafter. A desirable embodiment of my invention is illustrated in the accompanying drawing, in which:

Figure 1 is a view of my invention and the forward portion of an automobile, the valve being attached to the intake manifold of the automobile gas engine, the steam port of the valve being connected to the automobile radiator and the valve controlling element being shown in position on the steering post of the automobile.

Fig. 2 is a front view of the valve.

Fig. 3 is a sectional view of the valve taken on line x^3-x^3 of Fig. 2.

Fig. 4 is a view of the valve with the cover thereof removed, the parts of the valve being shown in such position as to admit a small amount of air and a maximum amount of steam.

Fig. 5 is a view similar to Fig. 4, the parts of the valve being in such position as to shut off the steam and to admit a maximum amount of air.

Fig. 6 is a sectional view of the valve taken on line x^6-x^6 of Fig. 4.

The valve comprises a receptacle 1, a valve disk 2 and a valve cover 3. The receptacle 1 has a threaded shank 4 extending from its rear wall which shank is adapted to screw into the intake manifold 5 at the entrance portion thereof of an automobile or other gas engine 6 as shown in Fig. 1, whereby the valve is connected to and supported on the manifold. The receptacle 4 may be formed with a nut 7 to which a wrench may be applied to screw the shank tightly into the manifold. The receptacle 1 is provided with a port 8 which extends through the shank 4 and establishes communication between the receptacle and manifold. The valve disk 2 is journaled on a stud 9 projecting from the front wall of the receptacle and is held under spring tension in position against the front wall of the receptacle by a spring 10 surrounding the stud and bearing at one end against the disk and at its other end against a disk 11 on the end of the stud, which disk is held on the stud in position against the spring by a cotter pin 12, extending through the stud. The front wall of the receptacle is provided with an air port 15 which is adapted to be closed by the disk 2 and opened when a notch 16 in the disk registers therewith, to admit air into the receptacle 1 to supply air through port 8 to manifold 5 and thence to the engine cylinders. The receptacle is provided with a recess 17 in its front wall with which communicates a port 18 extending through a threaded boss 20 which projects from the side of the receptacle. To the boss 20 is coupled, by threaded coupling

21, one end of a flexible tube 22, the other end of said tube being connected to and communicating with interior of the upper portion of the steam radiator 25 of the automobile. The receptacle is also provided with a port 26 which is associated with the recess 17, the port and recess being at the same distance from the center of the receptacle so as to register with an arc recess 27 struck from the center of the disk 2, whereby steam may be supplied from the radiator through the tube 22, port 18, recess 17, recess 27 and port 26 to the interior of the valve receptacle 1 and then through port 8 to the engine intake manifold 5 and finally to the engine cylinders. The disk 2 has an arm 30 projecting therefrom in which is swiveled a coupling 31 through which coupling extends a flexible rod 32 which is secured in the coupling by a set screw 33.

20 The cover 3 has a flange 35 which fits around the receptacle 1 and is secured thereto by screws 36, said flange being recessed at 37 to permit movement of the valve disk 25 arm 30. The front or covering wall 40 of the cover is perforated to admit air to the port 15. A bracket 41 projects from the cover 3 in which bracket is secured by set screw 42, one end of a tube 43, through which tube extends the rod 32. Said tube and rod extend through the automobile dash board and up the automobile steering post 45 and the upper end of the tube is secured to the steering post just below the steering wheel 46 by a clamp 47. The upper end of the rod extends out of the upper end of the tube and has a knob 50 thereon which may be grasped by the automobile driver to reciprocate the rod in the tube so as to oscillate the valve disk 2 to open and close the valve air and steam ports 15 and 26, respectively, and admit air or steam or a combination of both into the engine cylinders.

40 In the position of the valve disk 2 as shown in Fig. 4, the disk nearly covers the air port 15, the notch 16 registering with only a small portion of the port, so that only a small amount of air may be admitted by the valve into the manifold and engine cylinders, while the disk recess 27 registers with both the receptacle recess 17 and port 26 so as to completely uncover said receptacle recess and port to admit a maximum amount of steam into the manifold and engine cylinders. If the knob 50 is pressed slightly the disk 2 may be turned so as to cover the port 15 completely and shut off the air completely from the manifold and engine cylinders through said port and to admit only steam to the manifold and engine cylinders, the disk recess 27 remaining in registration with the receptacle recess 17 and port 26.

Upon pulling upwardly on the knob 50, 65 the disk 2 may be turned so that the notch

16 will register with and entirely uncover the port 15 to admit a maximum amount of air through said port into the manifold and engine cylinders, while the disk recess 27 will be out of registration with receptacle recess 17 and the disk will close said recess and shut off the steam from the manifold and engine cylinders.

The valve may be used as an air brake upon closing the gas throttle of the engine 75 with the car in gear and opening the port 15 completely, under which conditions so much air enters the manifold that it "kills" the engine and the compression of the pistons in the cylinders holds the car back. 80

I claim:

1. An auxiliary air and steam inlet valve adapted to be secured to the manifold of an internal combustion engine, comprising a valve casing having an outlet port leading to the manifold, and separate steam and air inlet ports, a rotatable disk controlling said steam and air inlet ports, said disk having a radial recess adapted to uncover said air inlet port, and an arcuate channel on its valve casing engaging face, a steam supply conduit, said channel being adapted to establish communication between said steam supply conduit and said steam inlet port for a substantial part of the rotation of said disk, a spring pressing said disk against said valve casing and a manually operated arm for rotating said disk, the size and position of said recess and said channel being so arranged as to permit the admission of air or steam or air and steam in varying proportion to said valve casing. 95

2. An auxiliary air and steam inlet valve adapted to be secured to the manifold of an internal combustion engine, comprising a valve casing having an outlet port leading to the manifold and separate steam and air inlet ports, a rotatable member controlling said steam and air inlet ports, said member having a radial recess adapted to uncover said air inlet port and an arcuate channel on its valve casing engaging face, a steam supply conduit, said channel being adapted to establish communication between said steam supply conduit and said steam inlet port for a substantial part of the rotation of said member, means for rotating said member, the size and position of said recess in said channel being so arranged as to permit the admission of air or steam or air and steam in varying proportions to said valve casing. 110

3. An auxiliary air and steam inlet valve adapted to be secured to the manifold of an internal combustion engine, comprising a valve casing having an outlet port leading to the manifold and separate steam and air inlet ports, a movable member controlling said steam and air inlet ports, said member having a recess adapted to uncover said air 125

inlet port, and an arcuate channel on its valve casing engaging face, a steam supply port, said channel being adapted to establish communication between said steam supply port and said steam inlet port for a substantial part of the movement of said member, the size and position of said re-

cess and said channel being so arranged as to permit the admission of air or steam, or air and steam in varying proportions to said valve casing.

In testimony whereof I have signed my name to this specification.

JOHN F. TEEL.
